UNITED STATES PATENT OFFICE.

GEORGE L. BENNETT, OF CLEVELAND HEIGHTS, OHIO.

BUILDING-WALL CONSTRUCTION.

Application filed September 21, 1926. Serial No. 136,742.

My invention relates to a building wall construction, and more particularly to one which, by reason of the construction and relation of different parts entering thereinto, is especially adapted for light work.

While a reduction in the labor cost of wall constructions is an important desideratum and is one object of the invention, I have provided a wall construction possessing great rigidity throughout, which will have highly desirable weather and fireproof properties.

A wall construction embodying my invention is substantially solid and is not subject to deterioration as a result of varying temperatures or weather conditions or from shrinkage of the material entering into the construction with a lapse of time.

While I employ metal studding and other metal parts, such are so protected as to be immune to deterioration from moisture seeping through, or exuding from stucco or plaster composition forming the outer or weather face of the wall. The body of the wall construction is formed mainly of material in slab form having heat insulating and waterproof properties, which not only affords protection for metallic portions of the wall, as above referred to, but which is an important factor in maintaining the desired temperature conditions within a building through the avoidance of excessive heat conduction through the wall in either direction. The body of the wall in addition to having the heat insulating, fire, and waterproof properties above referred to, affords a rigid backing permitting an effective working of the stucco forming the outer surface or the plaster forming the inner surface of the wall, when applying such materials thereto. The contour of the slabs forming this body, and the manner of connecting them to the studding is such as to not only permit the mounting of the slabs with the expenditure of little labor, but to permit the use of reinforcing meshing for the stucco or plaster walls so secured to the studding as to provide an adequate support for the material of the facings and make the likelihood of the separation of these facings from the wall body negligible.

In a wall construction embodying my invention, there are substantially no cracks or

crevices for the secreting of dust, dirt or vermin, thus affording a highly sanitary wall construction in addition to the various other properties referred to.

A finished wall construction embodying my invention is characterized by the presence of continuous stucco or plaster surfaces upon the opposite sides thereof, all metal portions entering into the construction being concealed by the body and facings of the wall.

Standard channel studding may be used in assembling of the wall construction, the slabs forming the body of the wall being so shaped as to co-operate therewith, means being provided to prevent any material movement of these slabs in relation to the studding. The various metallic portions of the structure may be readily assembled in the shop to simplify and cheapen the cost of erection of the wall.

The invention consists primarily in a building wall construction embodying therein spaced, fixed studs, substantially non-inflammable, non-absorbent, pre-formed slabs mounted between and secured in relation to adjacent studs, metal reinforcement at one side of said slabs, means secured to said studs supporting said metal reinforcement and spacing it from said studs and said slabs, a stucco facing upon said slabs and about said reinforcement, a metal reinforcement at the other face of said slabs, means secured to said studs supporting said reinforcement and spacing it from said studs and said slabs, and a plaster surfacing upon said slabs and about said last named reinforcement; and in such other novel features of construction and combination of parts, as are hereinafter set forth and described and more particularly pointed out in the claims hereto appended.

Referring to the drawings,

Fig. 1 is a view of a fragmentary section of a wall construction embodying my invention broken upon different vertical planes to disclose the construction thereof;

Fig. 2 is a section on the line 2—2 of Fig. 1;

Fig. 3 is a fragmentary portion of reinforcement and a fastener and spacer used with a thick surfacing such as stucco;

Fig. 4 is a similar view of reinforcement

and a spacer and fastener used with a thin surfacing such as plaster; and

Fig. 5 is a plan view of Fig. 4.

Like letters refer to like parts throughout the several views.

In a wall construction embodying the invention, I use metal studding *a*, preferably using, for economy's sake, channelled metal. The channels of the different studs are all 10 presented in the same direction, thus facilitating the mounting of the slabs forming the body of the wall in relation to these studs and to each other.

The studs *a* may be of any desired weight 15 or material, but preferably are of formed, sheet metal stock.

Mounted between adjacent studs are previously formed slabs composed mainly of a hardened plastic composition containing 20 or composed of materials having low heat conductivity. This material is also non-inflammable and non-absorbent or nearly so, so as to embody in the body of the wall, material which will not only check the transmission of heat to or from a building, but which will, in large measure, protect the metal of the studding from moisture which has a deteriorating effect thereupon.

One face of each slab *b* is rabbeted at opposite ends thereof, at *c* and *d*, not only to facilitate the fitting of one end of the slab, that adjacent the rabbet *c*, within the channel of a stud *a*, but to offset one face of the slab in relation to the studding and afford 35 clearance adjacent each stud for the fasteners used in mounting reinforcing meshing in relation to the studding and spaced away therefrom. The rabbet *c* is of greater length than the rabbet *d*, because the latter has merely a sliding fit in relation to the 40 under side of the channelled stud and is not required to extend within the channel as is the case with the portion of the slab adjacent the rabbet *c*.

45 The outwardly presented face of each slab in the wall construction is protected by a surfacing of waterproof material *e* which may take the form of asphaltum or other composition, or of waterproofed paper.

50 The fitting of the reduced end of the slab within the channel of a stud *a* prevents substantial movement of this end of the slab inwardly or outwardly of the wall, but to check a tendency of the other end of the slab 55 to move inwardly of the wall, outward movement thereof being restrained by means which will be hereinafter described, I provide a plurality of spring ratchet teeth *f* secured to the bottom of the channelled studs 60 at spaced distances in any desired manner, as by welding methods, which teeth are adapted to co-operate with a socket or sockets *g* formed in the material of the slab *b* at the end thereof adjacent the rabbet *d*.

65 Each slab is provided with a rabbet *c*'

of substantially the thickness of the metal of the studs, and at the end of the slab adjacent the rabbet *c*.

The rabbets *c* and *d* are of a depth to project well beyond the outer side flanges of 70 the studs *a*, thus leaving channels formed by contiguous vertical tiers of slabs at and upon opposite sides of each of the studs *a*. These channels are formed largely for the purpose of permitting the utilization of 75 spacers *h* secured in any desired manner, as by spot welding, to the side flange of each channel and at predetermined spaced distances from each other. These spacers *h* project well beyond the face of the slabs *b* 80 and serve as supports for a stiff wire mesh reinforcement *i* for a stucco or other plaster facing *j*, the mesh *i* being imbedded in the stucco and being spaced well away from the waterproofed surface *e* of the slab. By this 85 arrangement the slab *b* forms a firm backing against which the stucco may be trowelled or otherwise worked, thus ensuring great stability in this surface, particularly as steel studding is not subjected to such shrinkage 90 or warping as would in time tend to disrupt this stucco finish.

To facilitate the mounting of the wire mesh, I make the spacers and fasteners with a reduced head *h'*, having parallel downwardly directed oblique openings *h*² there-through adapted to receive a staple *h*³. This staple straddles a wire of the mesh, and as it is driven to place is so deformed by the 95 walls of the openings *h*² as to firmly lock 100 the staple in relation to the wire and to the spacers.

The spacers *h* in addition to rigidly supporting the wire reinforcement *i*, are also utilized to secure in position filler blocks *k* of cork composition or other suitable waterproof, substantially non-inflammable material, the dimensions of which are such as to fill the channels formed by the rabbets *c* and *d* of the slabs in adjacent wall 110 sections. These blocks may be of any desired length, and have openings for receiving the spacers, cut or molded therein in order to simplify the erection of a wall by 115 reducing the labor required on the construction job. The blocks *k* are held in position by means of metal washers *h*⁴ about the reduced end *h'* of the spacers, the staples *h*³ by engagement with this washer forcing it 120 down upon the filler block, and incidentally clinching the staples to ensure greater permanency in the attachment of the mesh reinforcement by such staples.

The filler blocks *k* are of a thickness to come substantially flush with the waterproofed face of the slabs *b*, thus ensuring a substantially continuous flat backing against which the stucco or other surface dressing may be worked. These blocks will also serve as an 125 effective barrier against the transmission of 130

heat and moisture from the stucco facing to the steel studding, thus limiting the possibility of the conduction of heat, to the spacers h and eliminating practically all possibility of water from the stucco or other surface dressing reaching the steel studding. The facing j of stucco or other similar plaster material being the outer face dressing of the wall will have considerable thickness, and the mesh i will be fairly heavy, the thickness of this dressing admitting of the use of heavy wire mesh and the spacing of it well away from the body of the wall.

The inner surface finish m of the wall, however, will be an ordinary plaster finish, much thinner than the stucco facing, and will not admit of the use of the heavy wire mesh reinforcement used for the stucco finish. Furthermore, it is possible to place the inner finish directly against the steel studding, since this plaster will dry out readily and is not subjected to inclement weather with a resultant possibility of the absorption of moisture and its transmission to the body of the wall and to the steel studding, as can occur with the dressing j .

The surfacing m has imbedded therein metal lathing n or other suitable metal reinforcement supported from the various studs a and spaced therefrom and from the body slabs b , by spacers o similar in construction to the reduced heads h' of the spacers and fasteners h , and having corresponding oblique parallel openings h^2 co-operating with staples o' passing through the metal lathing or other reinforcement and engaging same.

Some of the spacers o are permanently secured by spot welding or other methods to the inner vertical flanges of the studs a , the ends of the staples as they pass through the openings h^2 engaging this flange and being clinched as a result of this engagement.

With a light reinforcement, however, it will be found necessary to provide intermediate the studding, spacers and attachments for the reinforcement, these spacers, however, being attached directly, by means of the staples, to the body slabs which the staples will readily penetrate, the opposite points of each staple being directed at diverging angles to each other, so as to hold the spacers sufficiently firmly.

The slabs b and the studding a will, as in the case of the surfacing j , provide a rigid backing against which the plaster surfacing m may be trowelled or otherwise worked and thus permit a desired density of this facing, and the desired packing of same between the metal lathing or other reinforcement and the slabs b , and ensure great stability in this surface.

After the placing of the studding in a building, and when the progress of the construction work has advanced sufficiently

to admit of the completion of the walls, the slabs b are positioned between adjacent studs a by inserting the reduced end thereof, formed by the rabbets $c-c'$, in the channel of one stud a , and the other end of the slab pushed into position so as to substantially abut against the adjacent stud a . The rabbet d will permit the tilting of the slabs so as to facilitate this positioning thereof, each spring ratchet f yielding with the initial contact of the end of the slab therewith, but springing into the socket g of the slab co-operating therewith. When the position of the slab permits, they will readily fall upon the sills or stringers or upon other slabs. Each slab may be quickly placed in position, and when once in position will be firmly held by the side flanges of one stud, and by the spring ratchets f carried by the adjacent stud. These slabs may be very quickly placed in position without the aid of cement or other plaster.

The waterproofing surface e may be applied to the slab during its fabrication or may be applied thereto after installation.

It will be noted that the spacers h and n are not so positioned as to interfere in any way with the positioning of the slabs, and that when each slab is in position, the outer face thereof, that in which the rabbets c and d are formed, will be presented outwardly of the wall and will project well beyond the studs a .

When adjacent complete tiers of slabs have been installed, the filler blocks k are mounted upon the various spacers h upon each stud a , thus filling the space formed by the channel forming rabbets c of one tier of slabs and the co-operating channel forming rabbets d of the adjacent tier. When all of the blocks are in position from wall to ceiling upon any stud a , the outer side flange of the studs will be completely covered by the filler blocks k , and thus be protected from the finish j of stucco or other material, other portions of the studs being protected from such finish j by the blocks k . In fact, the only path for the transmission of heat or moisture through the wall will be formed by the spacers h , the dimensions of which are so small as to result in no objectionable amount of either heat, cold or moisture reaching the studding, or passing to or from the building.

When the filler blocks k are in position, the washers h^4 are placed over the spacers h , and the wire mesh reinforcement brought in position with relation to said spacers and where staples h^3 may be passed over some portion of the wire mesh and into the openings h^2 . The driving of these staples will hold the washers h^4 , and the blocks k therethrough in a manner to prevent movement of the blocks k , and will, at

the same time, firmly fasten the wire mesh in relation to the spacers and the body *b*. The rigidity of the wire mesh *i* is such that spacers *h* secured only to the studding are required, the regularity in the formation of such wire mesh permitting the spacers to be welded or otherwise secured to the studding in the shop.

The channel of the stud engaging one end of the slabs *b*, and the ratchet teeth *f* and blocks *k* engaging the other end of said slabs will hold said slabs against any material movement from pressure at either face of the slab. Hence when the wire mesh *i* has once been secured to the studding by means of the fasteners *h*, the plasterer may thoroughly work the stucco or other plastic composition so as to force it through the wire meshing firmly against the waterproofed face *e* of the slab *b* and against the blocks *k*, which may or may not have waterproof facing, as desired, these slabs being ordinarily of composition cork which is sufficiently impervious to moisture without such a facing.

A thoroughly worked stucco surfacing or finish upon said slabs and about said wire reinforcement *i*, has great durability. It will also be noted that the reinforcement is supported from the steel studding, so as to relieve the slabs of strains from the weight of this stucco.

The metal lathing or other reinforcement *n* is then mounted upon the studding *a* and upon the various slabs *b* intermediate adjacent studs by means of the spacers *o* and the wall plaster applied to such lathing or reinforcement, the rigidity of the body of the wall facilitating the thorough working of this plaster, thus increasing its durability. The major portion of the load of this plaster surface will be supported from the studs *a*, the intermediate spacers and fasteners *o* affording additional support for the lathing, however, and minimizing likelihood of the cracking of the plaster as a result of the sagging of the lathing intermediate the studs. The surfacing *m* constitutes the wall of a room, and is not subject to the same weather conditions as the stucco *j*, and consequently with the absence of warping, shrinkage or displacement of the studs *a*, this plaster *m* will hold firmly. Since there will be no material transmission of moisture to the slabs *b* from the facing *j*, the wall facing *m* will not suffer from frequent wetting and drying.

Both surfaces *j* and *m* will have a continuous uninterrupted outer face, no metal portions of the wall structure being exposed through such surfaces.

It is not my intention to limit the invention to the details of construction herein shown and described, it being apparent that

such may be varied without departing from the spirit and scope of the invention.

Having described the invention, what I claim as new and desire to have protected by Letters Patent, is:—

1. A building wall construction embodying therein spaced, fixed studs, substantially non-inflammable, non-absorbent, pre-formed slabs mounted between and secured in relation to adjacent studs, metal reinforcement at one side of said slabs, means secured to said studs supporting said metal reinforcement and spacing it from said studs and said slabs, a plaster facing upon said slabs and about said reinforcement, a metal reinforcement at the other face of said slabs, means secured to said studs supporting said reinforcement and spacing it from said studs and said slabs, and a plaster surfacing upon said slabs and about said last named reinforcement. 70 75 80 85

2. A building wall construction embodying therein spaced, fixed studs, substantially non-inflammable, non-absorbent, pre-formed slabs mounted between and secured in relation to adjacent studs, and having at the opposite edges of one face thereof channel forming rabbets, the portion of the block between said rabbets being spaced beyond said studs, combined fasteners and spacers secured to said studs respectively and extending beyond a face of said slabs, filler blocks of substantially non-inflammable, non-absorbent material occupying the channels formed by said rabbets and secured in position by means of said fasteners and spacers, metal reinforcement supported by said fasteners and spacers in spaced relation to said studs and said slabs, a plaster facing upon said slabs and about said reinforcement, a metal reinforcement at the other face of said slabs, means secured to said studs supporting said reinforcement and spacing it from said studs and said slabs, and a plaster surfacing upon said slabs and about said last named reinforcement. 90 95 100 105 110

3. A building wall construction embodying therein spaced, fixed, channelled metal studs, substantially non-inflammable, non-absorbent, pre-formed slabs, mounted between adjacent studs, and having at the opposite edges of one face thereof, channel forming rabbets whereby one end of said slabs may be fitted within the channel of a stud, and the portion of the block between said rabbets is spaced beyond said studs, combined fasteners and spacers secured to said studs respectively and extending beyond a face of said slabs, filler blocks of substantially non-inflammable, non-absorbent material occupying the channels formed by said rabbets and secured in position by means of said fasteners and spacers, metal reinforcement supported by said fasteners 115 120 125

- and spacers in spaced relation to said studs and said slabs, a plaster facing upon said slabs and about said reinforcement, a metal reinforcement at the other face of said slabs, 5 means secured to said studs supporting said reinforcement and spacing it from said studs and said slabs, and a plaster surfacing upon said slabs and about said last named reinforcement.

10 4. A building wall construction embodying therein spaced, fixed, channelled metal studs, substantially non-inflammable, non-absorbent, pre-formed slabs, mounted between adjacent studs, and having at the opposite edges of one face thereof, channel forming rabbets whereby one end of said slabs may be fitted within the channel of a stud, and the portion of the block between said rabbets is spaced beyond said studs, 15 spring ratchets upon the bottom of each stud, one end of each slab having a socket therein adapted to be engaged by said spring ratchets, combined fasteners and spacers secured to said studs respectively and extending beyond a face of said slabs, filler blocks 20 of substantially non-inflammable, non-absorbent material occupying the channels formed by said rabbets and secured in position by means of said fasteners and spacers, 25 metal reinforcement supported by said fasteners and spacers in spaced relation to said studs and said slabs, a plaster facing upon said slabs and about said reinforcement, a metal reinforcement at the other face of said 30 slabs, means secured to said studs supporting said reinforcement and spacing it from said studs and said slabs, and a plaster surfacing upon said slabs and about said last named reinforcement.

35 5. A building wall construction embodying therein spaced, fixed studs, substantially non-inflammable, non-absorbent, pre-formed slabs mounted between and secured in relation to adjacent studs, metal reinforcement at one side of said slabs, means secured to said studs supporting said reinforcement and spacing it from said studs and said slabs, a plaster facing upon said slabs and about said reinforcement, a facing of water- 40 proof material between said plaster facing and the continuous surface of said slabs, a metal reinforcement at the other face of said slabs, means secured to said studs supporting said reinforcement and spacing it from said studs and said slabs, and a plaster surfacing upon said slabs and about said last named reinforcement.

45 6. A building wall construction embodying therein spaced, fixed, channelled metal studs, substantially non-inflammable, non-absorbent, pre-formed slabs, mounted between adjacent studs, and having at the opposite edges of one face thereof, channel forming rabbets whereby one end of said slabs may be fitted within the channel of a stud, and the portion of the block between said rabbets is spaced beyond said studs, 50 spring ratchets upon the bottom of each stud, one end of each slab having a socket therein adapted to be engaged by said spring ratchets, combined fasteners and spacers secured to said studs respectively and extending beyond a face of said slabs, filler blocks 55 of substantially non-inflammable, non-absorbent material occupying the channels formed by said rabbets and secured in position by means of said fasteners and spacers, metal reinforcement supported by said fasteners and spacers in spaced relation to said studs and said slabs, a plaster facing upon said slabs and about said reinforcement.

60 7. A building wall construction embodying therein spaced, fixed studs, substantially non-inflammable, non-absorbent, pre-formed slabs mounted between and secured in relation to adjacent studs, and having at the opposite edges of one face thereof channel forming rabbets, the portion of the block between said rabbets being spaced beyond said studs, combined fasteners and spacers secured to said studs respectively and extending beyond a face of said slabs, 65 filler blocks of substantially non-inflammable, non-absorbent material occupying the channels formed by said rabbets and secured in position by means of said fasteners and spacers, metal reinforcement supported by said fasteners and spacers in spaced relation to said studs and said slabs, a plaster facing upon said slabs and about said reinforcement.

70 8. A building wall construction embodying therein spaced, fixed, channelled metal studs, substantially non-inflammable, non-absorbent, pre-formed slabs, mounted between adjacent studs, and having at the opposite edges of one face thereof channel forming rabbets whereby one end of said slabs may be fitted within the channel of a stud, and the portion of the block between said rabbets is spaced beyond said studs, 75 spring ratchets upon the bottom of each stud, one end of each slab having a socket therein adapted to be engaged by said spring ratchets, combined fasteners and spacers secured to said studs respectively and extending beyond a face of said slabs, 80 filler blocks of substantially non-inflammable, non-absorbent material occupying the channels formed by said rabbets and secured in position by means of said fasteners and spacers, metal reinforcement supported by said fasteners and spacers in spaced relation to said studs and said slabs, a plaster facing upon said slabs and about said reinforcement.

85 9. A building wall construction embodying therein spaced, fixed studs, substantially non-inflammable, non-absorbent, pre-formed slabs mounted between and secured in relation to adjacent studs, and having at the opposite edges of one face thereof channel forming rabbets, the portion of the block between said rabbets being spaced beyond said studs, combined fasteners and spacers secured to said studs respectively and extending beyond a face of said slabs, 90 filler blocks of substantially non-inflammable, non-absorbent material occupying the channels formed by said rabbets and secured in position by means of said fasteners and spacers, metal reinforcement supported by said fasteners and spacers in spaced relation to said studs and said slabs, a plaster facing upon said slabs and about said reinforcement.

95 10. A building wall construction embodying therein spaced, fixed studs, substantially non-inflammable, non-absorbent, pre-formed slabs mounted between and secured in relation to adjacent studs, and having at the opposite edges of one face thereof channel forming rabbets, the portion of the block between said rabbets being spaced beyond said studs, combined fasteners and spacers secured to said studs respectively and extending beyond a face of said slabs, 100 filler blocks of substantially non-inflammable, non-absorbent material occupying the channels formed by said rabbets and secured in position by means of said fasteners and spacers, metal reinforcement supported by said fasteners and spacers in spaced relation to said studs and said slabs, a plaster facing upon said slabs and about said reinforcement.

105 11. A building wall construction embodying therein spaced, fixed, channelled metal studs, substantially non-inflammable, non-absorbent, pre-formed slabs, mounted between adjacent studs, and having at the opposite edges of one face thereof, channel forming rabbets whereby one end of said slabs may be fitted within the channel of a stud, and the portion of the block between said rabbets is spaced beyond said studs, 110 spring ratchets upon the bottom of each stud, one end of each slab having a socket therein adapted to be engaged by said spring ratchets, combined fasteners and spacers secured to the other side of said studs respectively and to the slabs intermediate said studs, a metal reinforcement supported by said combined fasteners and spacers in spaced relation to said studs and said slabs, and a plaster surfacing upon said slabs and said studs and about said last named reinforcement.

115 12. A building wall construction embodying therein spaced, fixed, channelled metal studs, substantially non-inflammable, non-absorbent, pre-formed slabs, mounted between adjacent studs, and having at the opposite edges of one face thereof, channel forming rabbets whereby one end of said slabs may be fitted within the channel of a stud, and the portion of the block between said rabbets is spaced beyond said studs, 120 spring ratchets upon the bottom of each stud, one end of each slab having a socket therein adapted to be engaged by said spring ratchets, combined fasteners and spacers secured to said studs respectively and extending beyond a face of said slabs, 125 filler blocks of substantially non-inflammable, non-absorbent material occupying the channels formed by said rabbets and secured in position by means of said fasteners and spacers, metal reinforcement supported by said fasteners and spacers in spaced relation to said studs and said slabs, a plaster facing upon said slabs and about said reinforcement.

ble, non-absorbent material occupying the channels formed by said rabbets and secured in position by means of said fasteners and spacers, metal reinforcement supported by said fasteners and spacers in spaced relation to said studs and said slabs, a plaster facing upon said slabs and about said reinforcement, combined fasteners and spacers secured to the other side of said studs respectively and to the slabs intermediate said studs, a metal reinforcement supported by said combined fasteners and spacers in spaced relation to said studs and said slabs, and a plaster surfacing upon said slabs and said studs and about said last named reinforcement.

9. A building wall construction embodying therein spaced, fixed studs, substantially non-inflammable, non-absorbent, pre-formed slabs mounted between and secured in relation to adjacent studs, and having at the opposite edges of one face thereof channel forming rabbets, the portion of the block between said rabbets being spaced beyond said studs, combined fasteners and spacers secured to said studs respectively, each of

said combined fasteners and spacers including therein a reduced end having parallel, oppositely, obliquely extending openings therein, a metallic washer, and a staple adapted to pass through said openings and abut against said washer, whereby said staples will be spread and clinched when driven within said reduced portion, filler blocks of substantially non-inflammable, non-absorbent material occupying the channels formed by said rabbets and secured in position by means of said fasteners and spacers, metal reinforcement supported by said fasteners and spacers in spaced relation to said studs and said slabs, a plaster facing upon said slabs and about said reinforcement, a metal reinforcement at the other face of said slabs, means secured to said studs supporting said reinforcement and spacing it from said studs and said slabs, and a plaster surfacing upon said slabs and about said last named reinforcement.

In witness whereof I have hereunto affixed my signature this 7th day of September, 1926.

GEORGE L. BENNETT.
